UNITED STATES PATENT OFFICE.

HENRY C. MILLER, OF MILWAUKEE, WISCONSIN; FIRST WISCONSIN TRUST COMPANY, OF MILWAUKEE, WISCONSIN, EXECUTOR OF SAID HENRY C. MILLER, DECEASED.

TEMPORARY BINDER.

Application filed September 6, 1923. Serial No. 661,177.

This invention relates to temporary binders or loose leaf binders.

Objects of this invention are to provide a loose leaf binder which may be locked in any one of several adjusted positions to accommodate various thicknesses of included leaves, which will securely retain the parts in their adjusted position against accidental or unwarranted motion, which may be manufactured with great facility, and which is of inexpensive construction.

Further objects are to provide a loose leaf binder in which the two main elements may be locked by means permanently carried by the binder, if desired, in which the locking mechanism and the manipulating devices therefor occupy a minimum of space, and in which a positive wedging grip is secured by the locking mechanism.

Embodiments of the invention are shown in the accompanying drawings, in which:

Figure 1 is a plan view of the binder with portions broken away to illustrate the interior construction.

Figure 2 is a sectional view on the line 2-2 of Figure 1.

Figure 3 is a sectional view on the line 3-3 of Figure 1.

Figure 4 is a sectional view on the line 4-4 of Figure 1.

Figure 5 is an enlarged detail of a portion of the binding means.

Figure 6 is a side elevation partly in section of a further form of locking means.

Figures 1 to 5 showing the first form of the invention will be described. The temporary binder comprises a bottom portion which consists of a tubular metal member 1 from which uprights, preferably of the form

of cylindrical posts 2 extend. These uprights may, if desired, be made of a plurality of pieces adapted to be screwed together in a well known manner. The loose leaves 3 are adapted to be threaded upon the posts 2.

A top member consisting of a tubular sheet-metal channel 4 is provided with a pair of apertures 5 through which the post 2 may be readily passed. Thus after

the leaves have been threaded upon the posts 20 the top 4 is slipped into position and pressed firmly down against the leaves and locked.

The locking means comprises a plate 6 which is loosely held within the channel

section 4 by means of a rivet 7, for instance, and is provided with a pair of outwardly and upwardly extending terminal portions 8-8. These portions are secured to the bar 6 and are notched or curved, as indicated at 9 in Figure 1, so as to conform slightly to the curvature of the posts 2. The spacing of the posts and of the locking tongues 8 is such that the tongues may freely slide upon the posts in normal position.

In order to force the posts into engagement with the tongues 8, a sliding plate or binding plate 10 is provided and is swivelly joined to an adjusting or binding screw 11. This binding screw 11, as may be seen from Figure 5, may be provided with a shoulder 12 loosely received in a cut-out portion 13 in the plate 10 and may also be provided with a tip or extension 14 which is loosely received within a corresponding aperture in the plate 10, thus providing an extremely simple swivel connection. This connection prevents the plate becoming disconnected from the screw 11. The outer terminal of this binding screw 11 may be square and tapered, as indicated at 15 in Figure 5, and may have a knurled adjusting thumb nut 16 forced thereon so as to be permanently attached thereto. However, if desired, a removable key may be employed although the preferable form is to have the entire device ready for operation and self-contained without the necessity of employment of an additional instrument.

The binding screw is threaded through a block 17, (see Figure 2). This block is secured by means of rivets 18 (Figure 1) which pass through the outer shell or channel 4 and securely fix the block in position. A somewhat similar block 19 is provided for the other end of the channel 4 and is similarly riveted in position although, obviously, this block is not provided with a transverse aperture. Hinge members 20 are received in slots within the blocks 17 and 19 and are retained in position by means of the rivets 18. These hinge members carry the pintle rod 21. If desired, an additional hinge member 22 may be provided intermediate the ends of each of the channel members. The pintle rod is attached to the upper cover 23 in the usual manner.

Any desired means may be employed for finishing the ends of the channel member 4.

In the form shown shaped end members 24 are employed and are provided with tongues 25 (see Figures 1 and 2) which are bent inwardly into corresponding recesses formed 5 in the channel member. Obviously, other means may be employed for finishing the ends of the channel members.

The operation of the apparatus is as follows:—When it is desired to lock the cover 10 in position, the thumb nut 16 is rotated and forces the plate 10 into engagement with the right-hand face of the right-hand post 2. This forces the post against the tongue 8 and, due to the slight sliding motion of the 15 plate 6, forces the other tongue 8 against the other post. The last-mentioned post is engaged by the left-hand face of the aperture 5 of the channel member 4 as such channel member is drawn to the right in Figure 2 20 by the action of the screw and thus the posts are forced into firm binding engagement 25 with the spring tongues 8. Obviously, any tendency to slide the cover from the posts will result in a slight rocking motion of the tongues 8 causing them to bind more tightly against the posts 2.

Figure 6 shows a further form of the invention in which the channel member 26 is similarly provided with a bearing block 27 30 through which is threaded the clamping screw 28 adjustable by a manipulating nut 29 or key if desired. This clamping screw terminates in an enlargement or shoulder 30 which bears directly against one of the posts 2. This construction replaces the bearing 35 slide 10 (see Figure 5) of that formerly described and may cooperate with a type of locking bar similar to that indicated at 6 in Figure 2. However, a further type of locking bar, indicated generally at 31, is illustrated in Figure 6 and comprises a strap-like 40 body portion provided with integral upwardly turned terminal tongues 32.

It is to be understood that although the 45 base member is referred to as equipped with upwardly projecting posts and the top member as the removable member, that obviously 50 the members may be reversed without departing from the spirit of the invention. These terms, therefore, as used in the claims, 55 are not intended to limit the invention but are used merely for the sake of clearness.

It is further to be noted that the bottom member may be made slightly longer than

the top member so as to offer a certain degree of protection for the adjusting nut. 55

It will thus be seen that a temporary binder or loose leaf binder has been provided in which the removable or top member is securely clamped in position upon the upright 60 posts in a simple and effective manner, in which the device is entirely self-contained, in which inadvertent removal of the top member is prevented and in which a cheap and easily produced construction is employed. 65

Although a few forms of the invention have been described in considerable detail, it is to be understood that the invention may be variously embodied and is, therefore, to be limited only as claimed. 70

I claim:

1. A loose leaf binder comprising a bottom member having a pair of upwardly extending posts, a tubular top member having a pair of apertures therethrough for loosely receiving said posts, a locking bar normally free to move relatively to said posts located interiorly of said tubular member and having terminal upwardly and outwardly extending locking tongues and externally manually operable means extending into said tubular member for forcing said posts towards each other and into engagement with said locking tongues. 75

2. A loose leaf binder comprising a bottom member having a pair of upwardly extending posts, a tubular top member having a pair of apertures therethrough for loosely receiving said posts, a locking bar normally free to move relatively to said posts located 90 interiorly of said tubular member and having terminal upwardly and outwardly projecting resilient locking tongues and externally manually operable means extending into said tubular member for forcing said 95 posts towards each other and into engagement with said locking tongues, the resiliency of said locking tongues increasing the binding action between said posts and said tongues when said tubular top member is urged upwardly away from said bottom member. 100

In testimony that I claim the foregoing I have hereunto set my hand at Milwaukee, in the county of Milwaukee and State of Wisconsin. 105

HENRY C. MILLER.
